UNITED STATES PATENT OFFICE.

MARSHALL A. WIER, OF LONDON, GREAT BRITAIN.

IMPROVEMENT IN RAILWAY-CAR PASSENGER-REGISTERS.

Specification forming part of Letters Patent No. 148,791, dated March 17, 1874; application filed November 4, 1873.

To all whom it may concern:

Be it known that I, MARSHALL ARTHUR WIER, of No. 9 Great Winchester street, in the City of London and Kingdom of Great Britain, have invented certain Improvements in Apparatus for Registering and Checking the Entries and Exits of passengers to and from Tramway-Cars, Omnibuses, or other Carriages, of which the following is a specification:

My invention relates more especially to apparatus whereby the numbers and places of entry and exit of passengers to and from tramway-cars, omnibuses, or other carriages are indicated by self-acting means, independently of the conductor, so as to afford an accurate check upon the amount of fares paid to him; but parts of my invention are also applicable to registering apparatus which is not wholly self-acting.

In cases where convenient I employ an ordinary turnstile to register the entrance of passengers, and another to register their exit, or a single turnstile may be arranged to register both the entrance and exit of passengers.

In cases where, in consequence of contracted space, an ordinary turnstile cannot be employed, I use a turnstile, the arms of which are successively placed across the opening, and allowed to fall out of the way by means of cam-surfaces acting by the rotation of a turnstile, or, instead of a turnstile, I employ a swing-gate, connected by suitable mechanism with a second gate, (which may be adapted to slide or swing,) in such manner as to cause it to act in conjunction with it, so as to bar the way to a following passenger until the first has passed.

Whether the turnstile or swing-gate be employed, I prefer to connect it with the registering mechanism by means of pneumatic actuating apparatus; but mechanical, electric, or other suitable actuating apparatus may be employed for that purpose.

I effect the registration by the action of a pricker, point, or pencil upon a movable sheet of paper, and I prefer to arrange it in the peculiar manner by which I distinguish the numbers entering or leaving the vehicle at or between any of the several stations.

In order to secure the effects above referred

to, certain changes corresponding to the various stations on the route have to be effected in appropriate parts of the registering apparatus, in order to bring the actuating mechanism of the turnstile or swing-gate in unison with the proper part of the registering apparatus, according with the part of the route the vehicle may be on at any time.

To effect these changes automatically I employ what I call a governing apparatus in connection with the registering mechanism; and I sometimes effect this change in the registering apparatus by a projection thrown up in the rail or road (in the case of tramways) by the passage of the car, the projection acting upon a rod, or some pendent instrument in connection with and moving the governing apparatus.

Figures 1, 2, and 3 illustrate an arrangement of swing-gate, connected to and acting in conjunction with a slide-gate, which arrangement I find suitable in some cases where it is not convenient to have the rising and falling arms, described in reference to Figs. 1 and 2, as, for example, in tram-cars.

G is the swing-gate or bar, which, in its normal position, stands across the opening or entrance. H is the slide-gate, working in conjunction with the swing-gate. Its normal position is behind the swing-gate, and it is operated by the motion of the latter. The slide-gate may be arranged to slide horizontally out behind the person entering or leaving, as he pushes the swing-gate before him; but I prefer to make the slide-gate oscillate on a center-pin, I, motion being given to it in the following manner: To a convenient part of the swing-gate standard a cam, or, if preferred, two lever-arms, J J, is or are attached. Two chains, K K, are fastened, one on each side of the standard, either to the cam or levers, the other ends being fastened to the standard of the slide-gate in such manner that when the swing-gate is turned in either direction the slide-gate is pulled forward across the entrance, so as to bar the way to another person until the swing-gate is returned to its normal position, an effect obtained by a spring, L, attached to the back of the slide-gate standard, or to a tail-piece on its own standard, as shown

at M. By this arrangement one or other of the gates will always be across the entrance after a passenger has passed.

In order to prevent the slide-gate from striking the passing passenger, which may take place when it is caused to vibrate in a plane parallel to that of the normal position of the swing-gate, I cause the slide-gate to move out at an angle behind the passenger, and then to close up after him. The first of these movements I effect by making the slide-gate standard N to swivel slightly in a socket, O, by means of the chains K K, above described, which, for that purpose, are made to wind around the hollow standard N, so as to turn the slide-gate outward to the angle required to pass behind the passenger before it vibrates outward. The second of these movements I effect by means of a guide-piece, P, projecting from the standard of the swing-gate, so shaped, and acting upon the pin Q on the slide-gate standard, as to cause the latter to swivel in its socket in the direction opposite to that effected by the chain K K, thus closing up behind and following the passenger as he continues to turn the swing-gate G.

In order that the same effects shall obtain whichever way the swing-gate is turned, the slide-gate socket is caused to slide on the center-pin I by the action of the chains K K or guide-piece P, as the swing-gate turns so that the slide-gate shall always vibrate out on that side of the swing-gate from which the passenger is passing. The guide-piece P may be so shaped as to effect the sliding out of the slide-gate instead of employing the chains, but I prefer to use the latter means for that purpose.

Figs. 1^a and 1^b show another method of obtaining similar relative movements of the swing and slide gates. The pin Q on the slide-gate standard takes into a slot, Q¹, on a lever, P, on the axis of which is fixed the pulley or drum P¹. Chains P² and P³ are connected to this drum, and to arms P⁴ and P⁵ on the swing-gate center. Movement of the swing-gate thus imparts motion to the drum P¹, lever P, and from thence by the pin Q to the slide-gate, effecting both the sliding out and closing up motions. The counterbalance weight P⁶ restores the sliding and swing gates to their normal positions, when the latter is left free after the entrance or exit of a passenger.

To prevent passengers entering or leaving without being registered by passing in between the swing-gate and slide-gate as another person passes the reverse way, the pins R R on the slide-gate socket fall into the holes S S, when the slide-gate is drawn forward, whereby it is locked in position until the swing-gate shall have closed again sufficiently to slide the socket far enough toward the center of its fulcrum to disengage the pin from the hole, which will not take place until the swing-gate has nearly resumed its normal position, and,

therefore, will be too close to the swing-gate to admit of the presence of a person between them.

In order to prevent the slide-gate H from sliding out in front of the person entering the doorway, instead of behind him, by reason of the swing-gate G being pushed forward before the person is sufficiently close to it, the swing-bar G' may be employed above the swing-gate. This swing-bar is allowed to turn loosely on the hollow standard N to an extent limited by the pin and slot 12. The person entering naturally places his hand upon the swing-bar G', which yields before him, but has no effect upon the swing-gate until the person has advanced close enough thereto to allow the slide-gate to pass behind him.

The swing-gate may, if desired, be caused to fall back when pushed in either direction, in a manner somewhat similar to the slide-gate; or the swing-gate arm may be shortened when pushed either way by being made telescopic, such shortening being effected by a chain attached to the sliding arm and a cam or lever on the standard, or otherwise. By these means still less space may sometimes be made to suffice for the turnstile arrangements.

When convenient, I prefer to apply a registering apparatus direct to the turnstile or swing gate, for the purpose of registering the number of persons entering or leaving the car or carriage.

Figs. 5 and 6 illustrate a registering apparatus applicable to a turnstile capable of revolving continuously backward or forward, mechanism being so arranged as to register both the entrances and exits. A represents the axis of the turnstile, upon which is a notched disk, B, having a double series of four fingers, C C' and C', fastened thereto. The series of fingers C C are all disposed in one upper plane, the series of fingers C' C' are all in one lower plane, so that the series C C in revolving in the direction of the plain arrow operate upon the bell-crank lever D, and the series C' C', when revolving in the opposite direction, operate upon the bell-crank lever D'. These bell-crank levers are fitted with triggers E and E', which enable the fingers to pass their corresponding lever when revolving in one direction without acting upon it. The bell-crank levers are provided with pricker-points F and F', which puncture a strip of paper, G, traversed by the reels H H' against an elastic surface, I, by a step-by-step motion in the following manner: J is a spur-wheel sector, free to revolve on the pin K. L is a sector gearing with the spur-sector J, and having an arm, L', which is held against the notched disk B by a spring, M. A click on the spur-sector J takes into a ratchet-wheel on the reel H', which is prevented from turning too easily by a spring, N, which bears against it.

It will now be understood that whenever the turnstile makes a quarter revolution in either direction, the sector L is moved by the disk B,

and the spur-sector J is rotated, and with it the click, one or more teeth of the ratchet being thus taken up when the arm L' drops into the recess or notch on the disk B. The spring M draws the sector L back, and the reel is wound round by the click a step, the paper being then wound onto the reel H' off the reel H by so much. The same quarter revolution of the turnstile will, however, have caused one of the fingers C or C' to press upon one of the levers D or D', so as to cause the pricker to make a puncture on the paper strip, indicating the entrance or exit of a passenger, the entrances being shown by one row of punctures, the exits by another, as shown in Fig. 5. The pricker-levers D and D' are held against stops K¹ and K² by springs, as shown, when not being acted upon.

When the swing-gate is employed one finger only is necessary to operate both pricker-levers, which are then to be arranged one each side of such finger, and so centered that its motion to either side will operate one or other of such pricker-levers.

I have above described means by which the numbers entering and leaving a vehicle may be registered; but in cases where there are several stations on a line of route, with various fares payable for the various distances on it, it becomes necessary to register the numbers entering or leaving during the passage over each section of the road. I effect this by governing apparatus, which I will now proceed to describe.

Fig. 6 shows a governing apparatus, which is operated by a projection thrown up from the rail by the wheel-tread as the car passes over it, catching a pendent lever, which presses a piston into a cylinder, compressing air therein, and forcing it through a pipe so as to expand an air-chamber, N, in the registering apparatus, (see Fig. 5,) which expansion of the air moves the sector L through a larger arc, and the paper is thereby moved a greater distance than is given by the turnstile. A space be-

tween the sets of punctures is thus produced, indicating a station.

Fig. 7 shows a similar arrangement, but in which a pendent lever carrying a roller at its lower end rides over a part of road which is crowned so as to lift it up, and so operate the air-cylinder, or move suitable mechanical devices to effect the necessary changes.

I have only illustrated pneumatic and mechanical means for effecting the registration and governing effects; but, as I have before stated, electric or other suitable means may be employed for that purpose.

I claim—

1. The combination of the swinging gate G and vibrating gate H, the latter arranged to close behind the passenger, substantially as described.
2. The combination of the swinging arm G', having a limited movement, with the swinging gate H, substantially as described.
3. The guide p p, in combination with the vibrating gate H, arms J J, chains K K, and spring L, substantially as described.
4. The notched disk B upon the turnstile-shaft carrying fingers C C C C, in combination with the bell-crank levers D' D, having triggers E E² and prickers F F for piercing a moving fillet, G, substantially as described.
5. The combination of the lever X and cylinder X', bellows N, toothed sector-lever L, and fillet-moving device, connected by means of the tubes, links, and teeth, substantially as described.
6. The combination of the laterally-sliding collar O, having studs R R with the notched plates S S, substantially as described.
